FLUID CONTROL DEVICE

Walter H. Freygang, Essex Fells, N. J., assignor to
Specialties Development Corporation, Bloom-
field, N. J., a corporation of New Jersey

Application November 2, 1938, Serial No. 238,391

7 Claims. (Cl. 137—139)

The present invention relates to the release of carbon dioxide under pressure for the purpose of extinguishing fire, but, as will be readily understood, is capable of application for other purposes.

In its broader aspect the invention has reference to a device for releasing a fluid medium under pressure normally restrained by a pressure operable main fluid flow controlling member, in which an auxiliary or pilot member is provided to release a portion of the fluid medium under pressure to act on the pressure operable main fluid flow controlling member to thereby actuate the same.

In a more limited aspect the invention relates to a device of the type referred to in which a seat type valve, held onto its seat principally by the pressure of the fluid it confines, is interposed between the fluid under pressure and the delivery passage, and in which in addition to the main valve an auxiliary valve is provided, controlling a fluid flow passage through the main valve, fluid released by the auxiliary valve through said passage acting on the operating means of the main valve to actuate the same.

While the fundamental principles underlying the device in accordance with the present invention have been generally disclosed in the copending application of Daniel Mapes, Serial No. 237,009, filed on October 26, 1938, and entitled "Self-energizing fluid release device," now Patent No. 2,206,818 of July 2, 1940, the subject of the present application will be found to differ therefrom more particularly in the provision of novel means for the control of the pilot valve and the general arrangement of the operating mechanism.

It is a broad object of my invention to provide a fluid releasing device, in which the pressure of fluid in the container is utilized to operate the main fluid release device of the container.

It is a further object of the invention to provide a releasing device in which the main valve of a fluid container is operated by a fluid pressure operated member actuated by fluid initially released from the container by means of a pilot valve.

A more specific object of the invention is to provide in connection with a container having an outlet opening controlled by a seat type valve, a valve opening member, a fluid pressure actuable piston for operating said opening member to open the valve, and a quickly and positively actuating pilot fluid control valve to initially release

fluid from the container to operate the main valve.

Further objects and features of the invention, not specifically enumerated above, will become apparent as the invention is described in greater detail in connection with the accompanying drawing, wherein:

Figure 1 is a vertical sectional view of the fluid medium release device in accordance with my invention as applied to a high pressure fluid container.

Figure 2 is a detail of the device of Figure 1.

In Figure 1, 1 is a fluid pressure container for carbon dioxide of conventional design whose outlet is controlled by the release device in accordance with the present invention. This device has a valve body 2, threaded at 3 into the outlet of container 1. Body 2 is provided with a valve chamber 4, forming a valve seat 5, on which is seated by means of the pressure acting on it from within container 1 the main valve 6 consisting of a metallic frame 7 embedded in a body 8 of a resilient substance, such as rubber. Valve 6 is mounted on a hollow stem 9 of hexagonal section, which slidably extends through an outlet chamber 10 and an opening 11 in a partition 12 formed in valve body 2 past a leakage preventing gasket 13 held in place by a nipple 14 threaded into a recess in partition 12, and 20 which finally extends into chamber 15 where it carries, secured to it by means of threads 16, piston 17 movable in said chamber. Piston 17 carries leakage preventing packing ring 18 and on its nether side a seating ring 19 preferably 25 of a substance similar to rubber, which seats on a seat 20 formed by the "floor" of chamber 15 on the downward stroke of piston 17. A passage 21 through valve 6 and stem 9 which extends through piston 17 is controlled by pilot 30 valve 22, held in its place against main valve 6 by spring 23 supported in a recess 24 of the spider member 25 press-fitted into the nether opening of valve body 2, which spider also serves to 35 guide said pilot valve. A control rod 26 for the pilot valve 22 extends through passage 21 of the main valve 6 and valve stem 9, through the body of piston 17 and terminates anchored at 27 in the lower portion of thimble 28. Thimble 28 and with it control rod 26 are movable with respect 40 to a threaded recess 29 in piston 17 by means of the quick thread 30. An actuating member 31 to which is secured the turning handle 32 is 45 able to turn said thimble by means of the coupling piece 33 which is fastened by threads 34 on its upper portion into the actuating member

31 and which in form of a shank 35 keys into a corresponding groove 36 in the upper portion of thimble 28. Thimble 28 carries anchored in its upper portion a second control rod 37 which passes through groove 36, a central passage 38 in coupling piece 33, and into a recess 39 in actuating member 31 where it controls an exhaust valve 40, preferably made of a rubber-like material, which is urged by spring 41 onto a seat 42 formed on the uppermost portion of coupling piece 33. Recess 39 is vented to the atmosphere by means of angular passage 43 and a circular recess 44 in the valve cap 45, forming an annular space around actuating member 31. Valve cap 45 is threaded into valve body 2 by means of threads 46. 47 and 48 are leakage preventing packing gaskets, while 49 and 50 indicate a lock nut and a washer locking the assembly to actuating member 31. Passages 51 in thimble 28 establish a fluid flow connection between passage 21 and the upper part of chamber 15. Passage 52 serves to vent the lower part of chamber 15 to the atmosphere, while 53 shows the outlet port to which may be connected a discharge line to receive the escaping fluid medium, not shown in the drawing.

Fig. 2 is a top plan of spider member 25.

In the operation of my invention, a turning of handle 32 and with it of actuating member 31 and coupling piece 33 causes thimble 28 to descend in recess 29 by means of quick threads 30. Control rods 26 and 37 follow the descent of thimble 28, on the one hand permitting exhaust valve 40 to seat on valve seat 42, on the other hand pushing pilot valve 22 off its seat surrounding the mouth of passage 21 in main valve 6. Fluid medium under pressure, which, by virtue of apertures in spider member 25, is normally present in the space adjacent pilot valve 22, and is now able to pass through passage 21, passages 51 and out into the upper portion of piston chamber 15 from where it is not able to escape because of valve 40. As soon as it is of sufficient magnitude, the pressure on top of piston 17 pushes it downward, unseating main valve 6 against the fluid pressure in container 1 and allowing now the full discharge of fluid medium through outlet chamber 10 and outlet port 53. It may be remarked here that the top face of piston 17 is proportionately larger than the nether surface of main valve 6 so as to make possible the establishment thereon of a force sufficient to overcome the pressure acting on valve 6. Any air or fluid medium present in the lower part of piston chamber 15 that might oppose the descent of the piston is vented through vent passage 52. In shutting off the flow of the medium, handle 32 is turned in the reverse sense, causing the ascent of thimble 28 together with control rods 26 and 37. This permits spring 23 to return pilot valve 22 to its seat against the under side of main valve 6, and causes the unseating of exhaust valve 40. This cuts off the space atop of piston 17 from its supply of fluid pressure and permits any gas in said space to exhaust to the atmosphere through passage 38, recess 41 and out through passage 43. A combined action of spring 23 and fluid pressure acting on main valve 6, and now unopposed, returns the main valve to its seat 5.

From the foregoing description, it will be seen that I have provided a quickly and positively acting means for releasing fluid medium under pressure, where only a limited initial operating movement to open or to close is required. It

will be seen further that my invention accomplishes the various objects pointed out at the beginning of this specification. Finally, while my invention has been illustrated and described with specific reference to the accompanying drawing, it will be apparent to those skilled in the art that the invention resides in certain principles of operation and construction which may be embodied in various other forms of construction without departing in any manner from the spirit and scope of the invention, and I therefore do not wish to be limited to the specific disclosure, but rather to the scope of the appended claims.

I claim:

1. In a control device for a fluid medium under pressure, a main seat type valve, a fluid pressure actuatable piston of greater area adapted to operate said valve against the pressure of the fluid medium, a connecting member tying said main valve and piston, a pilot valve operable to control a fluid flow passage from the source of pressure to a space adjacent to said piston, an exhaust valve controlling an exhaust passage from said space to the atmosphere, a member controlling both the pilot and exhaust valves having a length less than the distance between said pilot and exhaust valves and adapted to alternately engage and disengage the pilot and exhaust valves, whereby one valve is closed before the other is opened, and actuating means for the controlling member.

2. In a control device for a fluid medium under pressure, a main seat type valve, a fluid pressure actuatable piston of greater area adapted to operate said valve against the pressure of the fluid medium, a connecting member tying said main valve and piston, a pilot valve adjacent to and seating on said main valve operable to control a fluid flow passage from the source of pressure to a space adjacent to said piston, said pilot valve being spring-loaded and structurally independent of the device, an exhaust valve controlling an exhaust passage from said space to the atmosphere, said exhaust valve being spring-loaded and unconnected with any other element, all of said elements being disposed substantially coaxially with respect to each other, a member controlling both the pilot and exhaust valve mounted in said piston for coaxial reciprocation with respect thereto and adapted to alternately engage and disengage said valves, whereby one valve is closed when the other is opened, and actuating means for the controlling member; said fluid flow passage controlled by the pilot valve extending through the main valve, the connecting member, and the controlling member; said exhaust passage extending through the controlling member and the actuating means; and said controlling member including elements adapted to extend through said fluid flow and exhaust passages for engaging and disengaging said pilot and exhaust valves upon reciprocation of the controlling member.

3. In a control device for a fluid medium under pressure, a main seat type valve, a fluid pressure actuatable piston of greater area adapted to operate said valve against the pressure of the fluid medium, a connecting member tying said main valve and piston, a pilot valve operable to control a fluid flow passage from the source of pressure to a space adjacent to said piston, said pilot valve being yieldingly urged toward its closing position, an exhaust valve controlling an exhaust passage from said space to the atmos-

phere, said exhaust valve being yieldingly urged toward its closing position, a member having a rotatable screw-threaded engagement with the piston controlling both the pilot and exhaust valves and adapted to alternately engage and disengage the pilot and exhaust valves, whereby one valve is closed when the other is opened, and actuating means for the controlling member.

4. In a control device for a fluid medium under pressure, a main seat type valve, a fluid pressure actuatable piston of greater area adapted to operate said valve against the pressure of the fluid medium, a connecting member tying said main valve and piston, a pilot valve adjacent to and seating on said main valve operable to control a fluid flow passage from the source of pressure to a space adjacent to said piston, said pilot valve being spring-loaded and structurally independent of the device, an exhaust valve controlling an exhaust passage from said space to the atmosphere, said exhaust valve being spring-loaded and unconnected with any other element, all of said elements being disposed substantially coaxially with respect to each other, a member having a rotatable screw-threaded engagement with the piston controlling both the pilot and exhaust valves for coaxial reciprocation with respect thereto and adapted to alternately engage and disengage said valves, whereby one valve is closed when the other is opened, and actuating means for the controlling member; said fluid flow passage controlled by the pilot valve extending through the main valve, the connecting member and the controlling member; said exhaust passage extending through the controlling member and the actuating means; and said controlling member including elements adapted to extend through said fluid flow and exhaust passages for engaging and disengaging said pilot and exhaust valves upon reciprocation of the controlling member.

5. In a fluid pressure piston operated valve, having a pilot and an exhaust valve, the combination of a piston, a control member for the pilot and exhaust valves, and actuating means for said control member, said control member having a rotatable screw-threaded engagement with the piston for coaxial reciprocation with respect thereto and for movement therewith and for

reciprocation with respect to said actuating means.

6. In a control device for a fluid medium under pressure, a main seat type valve, a fluid pressure actuatable piston of greater area adapted to operate said valve against the pressure of the fluid medium, a connecting member tying said main valve and piston, a pilot valve adjacent to and seating on said main valve operable to control a fluid flow passage from the source of pressure to a space adjacent to said piston, an exhaust valve controlling an exhaust passage from said space to the atmosphere, a member controlling said pilot valve and said exhaust valve extending through a portion of said fluid flow passage, said passage extending through the main valve, the connecting member and a portion of the controlling member, and actuating means for the controlling member comprising control member operating elements outside and inside said device whereby said control member upon actuation is adapted to move first relative to and then with said piston.

7. In a control device for a fluid medium under pressure, a main seat type valve, a fluid pressure actuatable piston of greater area adapted to operate said valve against the pressure of the fluid medium, a connecting member tying said main valve and piston, a pilot valve operable to control a fluid flow passage from the source of pressure to a space adjacent to said piston, said pilot valve being yieldingly urged toward its closing position, an exhaust valve controlling an exhaust passage from said space to the atmosphere, said exhaust valve being yieldingly urged toward its closing position, all of the said elements being disposed substantially coaxially with respect to each other, a member controlling both the pilot and exhaust valves having a length less than the distance between said pilot and exhaust valves, actuatable supporting means for said control member in said piston, whereby said control member is adapted for coaxial reciprocation with respect to the piston and to alternately engage and disengage the pilot and exhaust valves, one valve closing before the other is opened, and actuating means for the controlling member.

WALTER H. FREYGANG.
